CLAIM

The ornamental design for a combination skid plate and multiuse recovery point for receiver hitch, as shown and described.

DESCRIPTION

FIG. 1 is a perspective view;

FIG. 2 is a left side view;

FIG. 3 is a right side view;

FIG. 4 is a front view;

FIG. 5 is a back view;

FIG. 6 is a top view; and,

FIG. 7 is a bottom view.

The broken lines depict unclaimed portions and form no part of the claimed design. The dot-dash lines depict boundary lines of the claimed design.
